ADJUSTMENT MEANS FOR SIGHTING TELESCOPES

Eduard Reuss, Kassel, Germany, assignor to Hertel & Reuss, Kassel, Germany, a firm

Application July 6, 1954, Serial No. 441,318

Claims priority, application Germany December 4, 1953

8 Claims. (Cl. 33—50)

This invention relates to means for adjusting the cross-hairs or markings of sighting telescopes or any sight in regard to a target.

In sighting telescopes it has been known to employ means in the form of cross-hairs which may be displaced for the purpose of altering the elevation of sight or for serving to obtain a fixed point of setting or calibration for aiming purposes. In the first case, the cross-hair means or device is displaced in upward or downward direction. In the second case, the cross-hair device must be displaced from one side to the other.

Devices have been heretofore known which are equipped with special knobs for carrying out movements of adjustments or by which elevation adjustment of the sighting device is mechanically coupled to forcedly perform movements with the optical adjustment of the telescope.

It is an object of the present invention to do away with certain disadvantages inherent in these known adjustment devices and to provide means affording a simplified and easily and readily actuatable positive connection in regard to the elevation adjustment and lateral adjustment of a sighting telescope resulting in a space saving and compact device of marked efficiency.

It is still another object of the present invention to provide means facilitating an interfitting relationship or telescopic arrangement of the knobs for actuating a plurality of cam means, which are coaxially arranged and adjacent each other and are employable for accurately adjusting the cross-hairs of sighting telescopes.

Still another object of the present invention is to provide means conducive to a very efficacious and easily operable adjustment device for use in connection with sighting telescopes, which consists only of a relatively few parts, which can be readily assembled and disassembled, if necessary, only a minimum number of manipulations being necessary in order to bring about rapid operation of adjustment.

Another object is to provide means contributing to easy and quick vertical and longitudinal adjustments of a sight without great effort by only one hand of the operator and without requiring visual care for selective actuation of respective adjustment means.

The foregoing and other objects of the invention not specifically set forth and the manner and means by which they are realized will be better understood from the detailed description which follows when considered in connection with the accompanying drawing.

In the drawing:

Fig. 1 is a fragmentary sectional vertical view through a sighting device made in accordance with the invention.

Fig. 2 is a plan view on the cam disk as seen from below whereby parts positioned below the cam disk have been omitted for the sake of clarity.

In Fig. 1, the cross-hair device 1 is formed as sighting means in a sighting telescope. This cross-hair device is held within a hollow block member 2 which surrounds the guide for the light of the telescope (not shown).

2

Member 2 may be moved in a vertical direction to the longitudinal axis of the sighting telescope. For that reason member 2 is connected and guided relative to a further block member 3. The guidance of member 2 relative to block member 3 may be effectuated by means of dovetail-shaped guide means along a vertical axis (not shown).

In order to also move or displace the cross-hair device 1 in horizontal direction the second block member 3 is also provided with a dovetail-shaped end 4 which is slideable in a correspondingly shaped horizontal groove of a third carrier or block member 5. This latter member is connected in any appropriate manner, for instance, by any fastening means or screws with a housing 5a of the telescope.

Block member 2 first referred to, which carries the cross-hair device 1, is equipped with an abutment pin or follower 6 which adjusts the elevation movement of the cross-hair device, whereby one face of pin or follower 6 coacts and always remains in contact with the end face 7 of a tubular cam 8. Resilient or spring means 9 affixed by means of screws 9a to block member 5 acts below and against block member 2 to urge the same together with pin or follower 6 in a vertical direction with respect to the longitudinal axis of the instrument. Consequently pin or follower 6 will always be in contact with the end face 7 of the cam 8.

Block member 3 carries a pin 10 which is adapted to adjust the lateral movement of the cross-hair device whereby pin 10 coacts with a lateral cam surface 11 of cam disk 12 (Fig. 2). Resilient or spring means 13 fixed to block 3 at 13a urges pin 10 always in contact with the curved side face 11 of cam disk 12.

Cam disk 8 which serves to facilitate the sight or elevation adjustment is rotatably journaled in a fixed carrier plate 14 positioned on the telescope housing 5a. Disk 8 is provided with an annular groove 8a into which carrier plate 14 projects for guiding purposes and for retaining disk 8 in position on the instrument. Plate 14 may, for instance, be divided into two parts or pieces, so that the respective parts may be inserted in the annular groove 8a, thus providing a rotative journal or bearing for cam disk 8. In the present instance, carrier plate 14 is provided with a reinforcement rim 14a which is attached to the telescope instrument 5a in any suitable manner, such as by screws (not shown). Disk 8 has a lateral enlargement or extension 15 which is positioned and in contact above carrier plate 14 and is adapted to slidably engage the latter at 8b. The enlargement or rim 15 may be knurled or in any other way shaped in order to facilitate rotation thereof. Cam disk 8 as well as its enlargement rim 15 are provided with a bore 8c. Cam disk 12 has an extension or stub shaft 16 which runs in a bearing 19a, forming part of an intermediary disk-shaped element 19 which is screwed into carrier plate 14 by means of outer screw threads 19b. Stub shaft 16 is connected with a stepped-up extension 17a which is positioned within bore 8c.

This extension 17a has further a circular-shaped plate 17 provided with a center slot 17b. This top plate 17 forming a single piece with extension 17a and stub shaft 16 is accommodated within a recess provided in rim extension 15 of cam disk 8, whereby the end surface of plate 17 lies substantially flush with the end face of rim extension 15 as can be seen in Fig. 1. Disk-shaped plate 17 which serves for the adjustment of the cross-hair device 1 in lateral direction may be preset in its side position (zeroing-in), for instance, at the opening of a hunt, by employing a coin for the insertion in slot 17b and by rotatably moving plate 17. Thus one hand of the operator may only be used to bring about elevation adjust-

ment by means of rotating rim extension 15, as may be well understood.

In Fig. 2, the carrier plate 14 is shown together with other parts in plan view and as seen from below plate 14. All parts of the device therebelow have been omitted, such as, for instance, the housing 5a of the sighting telescope. Thus pins 6 and 10 are shown in cross-section and disk 12 is exposed to view together with its spiral-shaped peripheral curve 11 along which slides cylindrical pin 10.

In Fig. 2 is further shown the intermediary disk element 19 which is positioned at a level above cam disk 12, which intermediary disk 19 has a cut-out at 18. Through this cut-out is visible the end surface 7 of cam disk 8 coaxing with pin or follower 6 which, in this particular instance, is rectangular in cross-section.

The operation of the device will be readily gathered from the aforesaid disclosure and the objects of the invention are readily realized from the structural features herein shown and referred to.

It can thus be seen that there has been provided in accordance with the invention adjustment means for the cross-hairs in a sighting telescope, which is characterized by two coaxially positioned disk means forming knobs or manipulating means, of which one is adapted for elevation adjustment and the other for lateral adjustment of said cross-hairs, a peripheral cam-shaped surface on one of said disk means, an end cam-shaped surface on the other of said disk means, respective follower means cooperable with said cam-shaped surfaces, respective displaceable carrier means for said follower means disposed within said telescope, and resilient means for biasing said carrier means with said follower means against said cam-shaped surfaces, to thereby maintain contact of said follower means with said cam-shaped surfaces, respectively.

Various changes and modifications may be made without departing from the spirit and scope of the present invention and it is intended that such obvious changes and modifications be embraced by the annexed claims.

Having thus described the invention, and what is claimed as new and desired to be secured by Letters Patent, is:

1. Adjustment means for the cross-hairs in a sighting telescope comprising two coaxially positioned disk means of which one is adapted for elevation adjustment and the other for lateral adjustment of said cross-hairs, a peripheral cam-shaped surface on one of said disk means, an end cam-shaped surface on the other of said disk means, respective follower means cooperable with said cam-shaped surfaces, respective displaceable carrier means for said follower means disposed within said telescope, and resilient means for biasing said carrier means with said follower means against said cam-shaped surfaces, to

thereby maintain contact of said follower means with said cam-shaped surfaces, respectively.

2. Adjustment means according to claim 1, including manipulating means, respectively, forming parts of said disk means and terminating in end faces substantially flush with each other.

3. Adjustment means for the sighting means of a telescope having a housing comprising two coaxially and concentrically positioned rotatable members one encased within the other and, respectively, adapted for elevation adjustment and for lateral adjustment of said sighting means, a first cam-shaped face disposed on the end of one of said members, a second cam-shaped face disposed on the periphery of the other of said members, respective follower means cooperable with said cam-shaped faces and supported in said telescope housing, means biasing said follower means against said cam-shaped faces, to thereby maintain contact of said follower means with the latter, respectively, and means facilitating manipulation of said members and integral with the latter and terminating in end faces substantially parallel with the longitudinal axis of said housing and substantially level with each other.

4. Adjustment means according to claim 3, said manipulating means being concentrically disposed to each other on said telescope housing.

5. Adjustment means according to claim 3, including carrier means, respectively positioned within said telescope housing and supporting said sighting means, said follower means and said biasing means, respectively, said carrier means extending substantially in the direction of the longitudinal axis of said telescope housing.

6. Adjustment means according to claim 3, including means for guiding one of said rotatable members relative to the other of said rotatable members, said guiding means being stationary and affixed to said telescope housing.

7. Adjustment means according to claim 6, wherein one of said members is provided with a guide groove, said guide means projecting into said guide groove of said one member.

8. Adjustment means according to claim 6, said guiding means being provided with thread means, and bearing means for the other of said members and threadedly engaging the threads of said guiding member, thus spacing said other member from said guiding means, which engages said one member.
